2,513,812

CONTROLLING DEVICE FOR HOISTS

Gordon F. McClay, Sherbrooke, Quebec, Canada,
assignor to Ingersoll-Rand Company, New
York, N. Y., a corporation of New Jersey

Application July 26, 1946, Serial No. 686,399

7 Claims. (Cl. 187—35)

1

This invention relates to hoists, and more particularly to a controlling device for hoists equipped with clutch means for connecting the hoist drum to the driver.

It is an object of the invention to at all times assure engagement of either the clutch or the brake with the drum.

Another object is to enable the drum engaging and releasing movements of the clutch and brake members to be controlled by a common controlling device.

A more specific object of the invention is to prevent the unclutching of a hoist drum until the brake is applied and to obviate the chances of releasing the brake before the drum is connected to the driver.

Other objects will be in part obvious and in part pointed out hereinafter.

In the drawings accompanying this specification and in which similar reference numerals refer to similar parts:

Figure 1 is a side elevation of a hoisting mechanism positioned at the mouth of a mine shaft,

Figure 2 is a perspective view of a hoist equipped with a controlling device constructed in accordance with the practice of the invention,

Figure 3 is a perspective view, partly broken away, of the controlling device, and

Figure 4 is a transverse view taken through Figure 3 on the line 4—4.

Referring to the drawings, and at first more particularly to Figure 1, 20 indicates a mine shaft the mouth of which is spanned by a frame 21 supporting a sheave 22 for a cable 23 having an end attached to a cage 24 and being wound upon the drum 25 of a hoist 26.

The drum 25 is capable of free rotation upon a shaft 27 driven by a motor 28 and supported by bearing pedestals 29, and the driving connection between the shaft 27 and the drum 25 is effected by a clutching device 30 having shoes 31 for frictional engagement with an internal cylindrical surface 32 in the end of the drum 25. The shoes 31 are supported by links 33 that are pivotally connected to the shoes and to a clutch collar 34 slidably interlocked with the shaft, and the collar 34 is actuated axially of the shaft 27, for imparting drum engaging and releasing movement to the clutch shoes, by an engine 35 supported by one of the bearing pedestals 29.

The engine 35 comprises a cylinder 36 having a piston chamber 37 and a piston 38 therein operatively connected to the clutch collar 34. The piston 38 is of the differential type having

a large pressure surface 39 at one end and an opposed pressure surface 40 of smaller area than the pressure surface 39. On the latter end of the piston is a stem 41 that slides through the end of the cylinder 36 and has a bore 42 for the reception of a rod 43 an end of which is connected pivotally to the cylinder by a pin 44. The opposite end of the rod is connected in like manner to an arm 45 keyed to a shaft 46 interlocked with a clutch yoke 47 that reciprocates the collar 34.

The braking mechanism for the drum 25 may also be of a well known type and includes a pair of brake shoes 48 arranged at opposite sides of the drum 25 and applied to and released from the drum by a braking engine 49 and suitable linkage indicated, in general, by 50. The engine 49 is of the vertical type. Its cylinder 51 is supported by a frame 52 that rests upon a base 53 and contains a piston 54 having a rod 55 that extends slidably through a head 56 at the lower end of the cylinder. The rod 55 is connected to a crosshead 57 slidable in the frame 52 and connected, by means of a pivot pin 58, to a bar 59 of the linkage 50. The pin 58 also supports a pair of arms 60 that hang down along the frame 52 and have a cross-bar 61 at their lower ends to support a plurality of weights 62 that tend constantly to apply braking force to the brake shoes.

Movement of the piston 54, for imparting drum-releasing movement to the brake shoes, is effected by motive fluid acting against the lower surface 63 of the piston. Such motive fluid, as for example oil, is conveyed to the cylinder by a conduit 64 connected to a valve mechanism 65 which, in accordance with the practice of the invention, serves to control the actions of both the brake engine 49 and the clutch engine 35. The motive fluid is drawn from a reservoir 66 by a pump 67 and delivered to an accumulator 68 having a discharge conduit 69, a branch 70 of which is connected to the cylinder 36 to subject the pressure surface 40 of the piston 38 constantly to motive fluid.

The motive fluid serving to lift the piston 54 passes through the cylinder 36 and is conveyed therefrom by a conduit 71 leading to the valve mechanism 65. The conduit 71 is connected to an intermediate portion of the cylinder 36 and is uncovered by the piston 38 only when the said piston reaches, or closely approaches, the limiting position to which it is actuated by the motive fluid acting against the pressure surface 40.

The motive fluid that actuates the piston 38

in the opposite direction passes through the valve mechanism 65. It is conveyed thereto by a branch 72 of the conduit 69, and a conduit 73 leads from the valve mechanism 65 to the cylinder 36 to convey fluid to the pressure surface 39.

The valve cage 74 of the valve mechanism 65 has a valve chamber 75 that communicates with the conduits 71, 64, 73 and 72 through ports 76, 77, 78 and 79, respectively. These ports are arranged in the order named from the left hand end of the valve cage 74, as shown in Figure 3, and between the ports 77 and 78 is a port 80 that communicates, through a chamber 81 in the lower portion of the valve cage 74, with a discharge port 82 opening into a recess 83 that has an outlet conduit 84 leading to the reservoir 66.

The ends of the valve chamber 75 are constantly open to the atmosphere, through vents 85, to assure free movement of a valve 86 controlling the ports of the valve chamber. The valve 86 is of the spool type. It is reciprocated through the instrumentality of suitable linkage actuated by a lever 87, located on the operator's platform 88, and has a pair of end heads 89 and 90 and a flange 91 between and of the same diameter as the heads and connected thereto by stems 92. The head 89 controls the port 76 and also controls communication between the port 76 and the port 77, the flange 91 controls the flow of fluid from the ports 77 and 78 to the port 80, and the head 90 controls the port 78 and also controls communication between said port 78 and the port 79.

On the valve head 89 is a stem 93 that projects from the cage 74 and is interlocked with a yoke 94 on the free end of an arm 95 of a bell crank 96 pivoted at its angle upon a pin 97 supported by the valve cage. The free end of the other arm 98 of the bell crank is pivoted to an end of a link 99, and a pivot pin 100 connects the link 99 to an end of a link 101 pivoted to an arm of a rocker 102. The rocker 102 is pivoted intermediate its ends upon a pin 103 supported by a bearing 104, and the opposite arm of the rocker is pivoted to a rod 105 that is connected, for pivotal movement, to an arm 106 on the lower end of the lever 87 which is pivoted, upon a suitable support, for swinging movement to its controlling positions.

These positions, designated A, B, C and D, are respectively the position to which the lever 87 is moved for releasing the brake, for moving the clutch into engagement with the drum, for applying the brake and to disengage the clutch from the drum.

During the normal operation of the hoist, the lever 87 is shifted to the positions indicated by the letters A, B, C and D, and its movement is transmitted through the linkage connecting the arm 106 with the valve stem 93 for shifting the valve 86 to its different port controlling positions. During such operation the pin 100 floats with the links 99 and 101 along an arcuate path and is restrained to such path by a link 107 pivoted upon the pin 100 at one end and at its other end to the upper end portion of a bar 108.

The lower end of the bar 108 is pivotally connected to an extension 109 on the valve cage, and on the end of the bar adjacent the link 107 is a tooth 110 for engagement with a hook 111 of a latch 112. The latch 112 is pivoted intermediate its ends, for free swinging movement, upon a pin 113 supported by an arm 114 on the valve cage, and the hook end of the latch is heavier than the opposed end 115 to maintain the hook 111 interlocked with the tooth 110. A rod 116 holds the

tooth 110 against the hook 111. This rod is slideable in the valve cage and has a head 117 that bears against an intermediate portion of the bar 108 and is pressed thereagainst by a compression spring 118 encircling the rod 116 and seating against the valve cage 74.

The latch 112 and the bar 108 are normally interlocked with each other, in the manner described, and the bar is released only in the event of the over-winding or over-speeding of the drum. The means effecting the disengaging movement of the latch comprises a solenoid 119 placed above the arm 115 of the latch in such relation therewith that when the solenoid is energized a slight space will exist between the end of the armature 120 and the arm 115.

In the circuit 121 conveying electrical current to the solenoid is a limit switch 122 that is so positioned on the frame 21 that it will be opened by the cage 24 whenever the cage is lifted above its normal stopping position. The circuit 121 is further provided with a switch 123, similar to the switch 122, for opening the circuit 121 in the event that the hoist drum exceeds a certain predetermined speed. The switch 123 is tripped, for opening the circuit 121, by the controller 124 of the hoist, and is so positioned that when the spring bar 125 opposing the fly-weights 126 of the controller is depressed to a predetermined point it will come into contact with and open the switch 123.

The hoist controller may be of any suitable and well known type and, in addition to its normal functions, serves to impart movement to a wedge-shaped cam 127 that controls the degree of end-wise movement of the rod 116 when the latch 112 is disengaged from the bar 108. The cam 127 slides upon an outer end surface 128 of the valve cage 74 and has a stem 129 at its narrow end extending upwardly and pivotally connected to an end of a rocker 130 pivoted on the base of the controller 124. The rocker is actuated, in a well known manner, by a limit-cam 131 of the controller in such wise that when the cage 24 approaches or reaches the end of its travel the cam 127 will be moved upwardly to bring its wide end into the transverse plane of the rod 116.

The rod 116 extends through the cam and carries a pin 132 having rollers 133 thereon for engagement with the cam, and on the portion of the rod 116 lying within the chamber 81 is a valve flange 134 to control the flow of fluid from the chamber 81 to the port 82.

In the operation of the device, whenever it is intended to establish a driving connection between the drum and the driver, the lever 87 is placed in the controlling position A. The valve 86 will then occupy a position wherein the flange 91 blocks off communication between the ports 77 and 80 and the port 76 is uncovered by the head 89. Some of the motive fluid acting against the pressure surface 40 to hold the piston 38 in position to press the clutch shoes against the surface 32 of the drum then flows from the piston chamber 37 through the conduit 71, the valve chamber 75 and the conduit 64 into the cylinder 51 and raises the piston 54. This movement of the piston, transmitted through the bar 59 and the linkage 50, releases the braking pressure from the shoes 31 and the drum is then free to rotate with the driver.

When the cage 24 has been moved to a desired position the lever 87 is moved to the controlling position C. The valve 86 will then occupy a position wherein the head 89 overlies the port 76

to cut-off the flow of fluid from the piston chamber 37 to the valve chamber and the port 77 will be in communication with the port 80 through the space between the head 89 and the flange 91. The motive fluid will then escape from the cylinder 51 through the conduit 64, the valve chamber 75 and the chamber 84, thence pass through the port 82, the recess 83 and the conduit 84 into the reservoir 66. The crosshead 57 will then descend and cause the linkage 50 to press the brake shoes 48 against the drum 25.

After the brake has been thus applied to the drum the lever 87 is shifted to the position designated D. The valve 86, as viewed in Figure 3, will then occupy a position wherein the space between the head 90 and the flange 91 affords communication between the ports 78 and 79 and the head 89 will blank-off the port 76. Motive fluid then flows through the conduit 12, the ports 79 and 78 and through the conduit 13 into the piston chamber 37 against the pressure surface 39. Inasmuch as said pressure surface 39 is of larger area than the opposed surface 40 the piston 38 will be shifted toward the right hand end of the piston chamber 37 and move the clutch shoes 31 out of engagement with the drum.

The drum 25 will then be held immovable by the brake shoes, and when it is intended to move the cage 24 to another station the lever 87 is moved to the position designated B. The valve is thereby placed in a position where the head 89 will blank-off the port 76 and the space between the flange 91 and the head 90 will afford communication between the ports 78 and 80. The motive fluid acting against the pressure surface 39 will then escape through the valve chamber 75 and associated passages to the reservoir 66, and the motive fluid in the opposite end of the piston chamber 37 will shift the piston 38 and move the clutch shoes into engagement with the drum. Thereafter, the lever is moved to the position designated A for shifting the valve to its right hand limiting position. In this position of the valve the ports 76 and 77 will be in communication with each other through the space between the head 89 and the flange 91 and motive fluid will flow from the piston chamber 37 into the cylinder 51 and lift the piston 54 for releasing the brake from the drum.

These operations are repeated, as required, to move the cage from place to place along the shaft 20, and whenever the speed of the hoist exceeds a certain predetermined rate the weights 126 of the controller 124 will cause the spring rod 125 to trip the switch 123 and open the circuit 121 of the solenoid 119. The armature 120 will then drop down upon the arm 115 and rock the hook 111 of the latch out of engagement with the claw 110 and the spring 118 will shift the rod 116 toward the right until the rollers 133 seat against the cam 127.

This movement of the rod 116, transmitted through the links 107 and 99 and the bell crank 96, will move the valve 86 leftward to a position where the head 89 blanks off the port 76 and the space between the head 89 and the flange 91 affords communication between the ports 77 and 80. The fluid will then escape from the cylinder 51 through these channels to the reservoir 66, and the piston of the braking engine 49 will descend and press the brake shoes against the drum 25.

The rate at which the braking force is then applied to the drum will depend upon the relation of the valve 134 with respect to the port 82

and, of course, also upon the adjustment of the hoist controller for changing the position of the cage 24. For example, while the cage 24 is moving through an intermediate portion of its range of travel the cam 127 will be in the position it normally occupies and will permit the valve 134 to closely approach the port 82 and exert a throttling action upon the fluid passing therethrough. The piston of the braking engine will, under these circumstances, descend at a comparatively slow rate and the brake setting will take place gradually. But if the cage reaches a position for which the hoist controller 124 has been adjusted to act, the limit-cam 131 thereof will engage and tilt the rocker 130 and move the cam 127 upwardly. In this way, the cam will retract the rod 116 and the valve 134 and increase the flow area between the valve 134 and the port 82. The fluid will then flow freely from the cylinder 51 and the setting of the brake will take place more rapidly.

This automatic shifting of the valve 86, independently of the lever 87, for applying the brakes to the drum will, of course, also take place when the cage 24 is lifted beyond its normal stopping place at the mouth of the shaft 20. In such event, the cage will engage and open the switch 122, to deenergize the solenoid 119, and the armature 120 will drop and trip the latch 112 to permit the spring 118 to shift the valve 86 for setting the brake.

From the foregoing description it will readily be appreciated by those skilled in the art that, owing to the fact that both the brake engine and the clutch engine are controlled by a single controlling device, there is a positive interlock between the clutch and the brake that will preclude the chances of releasing both from the drum at the same time.

I claim:

1. A controlling device for hoists having a drum, a driver therefor and clutch and brake members for the drum, said controlling device comprising pressure responsive actuators for the members, a valve for controlling the motive fluid supply to both actuators for causing said actuators to impart drum-engaging and releasing movement to the members, a manually operable member for normally shifting the valve to its various controlling positions, and means for shifting the valve independently of the manually operable member to cause one actuator to impart drum-engaging movement to the brake.
2. A controlling device for hoists having a drum, a driver therefor and clutch and brake members for the drum, said controlling device comprising pressure responsive actuators for the members, a valve for controlling the motive fluid supply to both actuators for causing said actuators to impart drum-engaging and releasing movement to the members, a manually operable member for normally shifting the valve to its various controlling positions, spring-pressed means for shifting the valve independently of the manually operable member to cause one actuator to impart drum-engaging movement to the brake, a latch for holding the spring-pressed member normally inoperative, and a solenoid acting when de-energized to release the latch from the spring-pressed member.
3. A controlling device for hoists having a drum, a driver therefor and clutch and brake members for the drum, said controlling device comprising pressure responsive actuators for the members, a valve for controlling the motive fluid

supply to both actuators for causing said actuators to impart drum-engaging and releasing movement to the members, a manually operable member for normally shifting the valve to its various controlling positions, spring-pressed means for shifting the valve independently of the manually operable member to cause one actuator to impart drum-engaging movement to the brake, a latch for holding the spring-pressed member normally inoperative, a solenoid for releasing the latch from the spring-pressed member, and switch means for controlling the energization of the solenoid acting in response to the speed of the hoist.

4. A controlling device for hoists having a drum, a driver therefor and clutch and brake members for the drum, said controlling device comprising pressure responsive actuators for the clutch and brake members, a valve for the supply of motive fluid to the actuators said valve having extreme and intermediate controlling positions, ports and passages at said intermediate position to conduct motive fluid to an actuator to engage the clutch and brake members with the drum, other ports and passages at one extreme controlling position to conduct motive fluid to an actuator to disengage the brake members from the drum, still other ports and passages at the other extreme controlling position to conduct motive fluid to an actuator to disengage the clutch members from the drum, and manually controlled means for shifting the valve to the different controlling positions.

5. A controlling device for hoists having a drum, a driver therefor and clutch and brake members for the drum, said controlling device comprising pressure responsive actuators for the clutch and brake members, a valve casing having a chamber, ports in the valve casing, conduits connecting the chamber with the actuators through the ports in the valve casing, a manually operable valve in the chamber said valve having extreme and intermediate controlling positions, and passageways in the valve for controlling the flow of motive fluid through the ports and passages to engage the clutch and brake members with the drum at the intermediate valve position and to cause disengagement of the brake members from the drum at one extreme valve position and disengagement of the clutch members from the drum at the other extreme valve position.

6. A controlling device for hoists having a drum, a driver therefor and clutch and brake members for the drum, said controlling device comprising pressure responsive actuators for the clutch and brake members, means for constantly urging the actuators to engage said members

with the drum, a valve casing having a chamber therein, ports in the valve casing, conduits connecting the chamber with the actuators through the ports in the valve casing, a manually operable valve in the chamber for the ports having extreme and intermediate controlling positions, and passageways in the valve adapted to uncover ports and passages to communicate, at one extreme controlling position, motive fluid to the actuators to effect disengagement of the brake members from the drum end, at the other extreme controlling position, disengagement of the clutch members from the drum and to uncover other ports and passages at the intermediate controlling position to exhaust the motive fluid from the actuators and allow said engaging means to effect engagement of the clutch and brake members with the drum.

7. A controlling device for hoists having a drum, a driver therefor and clutch and brake members on the drum, said controlling device comprising pressure responsive actuators for the clutch and brake members, means for constantly urging the actuators to engage said members with the drum, a valve casing having a chamber, ports in the casing for the chamber, conduits connecting the ports to the actuators for conveying motive fluid to and from the actuators, a reciprocable valve in the chamber, manually operable means for shifting the valve from one extreme controlling position to another extreme controlling position through a pair of intermediate controlling positions, and passageways in the valve to uncover and convey motive fluid to the brake actuator conduit at one extreme controlling position to disengage the brake members from the drum and to uncover and convey motive fluid to the clutch actuator conduit at the other extreme controlling position to disengage the clutch members from the drum and to communicate the actuator conduits with a port in the casing to exhaust the motive fluid from the actuators and allow said engaging means to engage the members with the drum.
